UNITED STATES PATENT OFFICE.

WALTER H. BALTES, OF MILWAUKEE, WISCONSIN.

HOIST.

1,402,469.

Specification of Letters Patent.

Patented Jan. 3, 1922.

Application filed December 8, 1920. Serial No. 429,046.

To all whom it may concern:

Be it known that I, WALTER H. BALTES, a citizen of the United States, residing at Milwaukee, county of Milwaukee and State of Wisconsin, have invented new and useful Improvements in Hoists, of which the following is a specification.

This invention relates to hoists and is particularly directed to a hand operated hoist. Objects of this invention are to provide a hoist of maximum strength without producing an elaborate or bulky mechanism; to provide a hoist in which the strains are distributed so that no single bearing is subjected to the major stresses; and to provide a hoist in which the major portion of the strains are borne by an integral structure thereby minimizing distortion, breakage, and the chains supporting parts becoming detached.

Further objects are to provide a hoist in which a minimum amount of machine work is necessary and in which a relatively small number of parts is required.

Further objects are to provide a hand hoist in which the worm wheel housing is closed by the worm wheel, and in which the worm wheel housing and hoisting drum support are of integral formation, thereby both materially lessening the cost of production and the chance of separation of the parts under stresses.

Further objects are to provide novel means of securing the parts in operative relation so that a very small number of operations is required in assembling, and to produce a hoist in which the time required for assembling and fitting the parts together is materially reduced.

An embodiment of the invention is shown in the accompanying drawings, in which—

Fig. 1 is an end elevation of the hoist.

Fig. 2 is a sectional elevation thereof on the line 2—2 of Fig. 1.

Fig. 3 is a sectional view on the line 3—3 of Fig. 2.

Fig. 4 is a plan view of the hoist with parts shown in section.

The hoist comprises a casing 1 which has integrally formed therewith a bearing 5 spaced laterally from such casing and joined by means of members 2 and 3 and a vertical strut or connecting member 4. The casing 1 is substantially cylindrical and is provided with inner annular bearing faces 6 and 7 which are adapted to form bearing surfaces

for the worm wheel 8. The face 7 is formed upon a member which has an outwardly projecting portion 9 adapted to fit within a correspondingly recessed portion of the worm wheel. The casing is open at both ends and has at its lower portion a transverse cylindrical part 10 adapted to house the worm. The inwardly directed bearing member 5 may be centrally cored if desired to lighten the structure, and the upper or supporting portion of the strut 4 may be webbed or flanged to provide requisite strength. The casing has swivelly joined thereto a supporting hook 11 which may be conveniently passed through the member 2, this supporting member being substantially in line with the load bearing chain of the hoist. The worm wheel 8 is provided with bearing faces 12 and 13 adapted to contact with the faces 6 and 7, the bearing being primarily at 7, although it may, if desired, be designed to have a bearing at the surface 6. The worm wheel 8 has integrally formed therewith a hoisting drum 14 which is hollow as indicated at 15 and designed to rest upon the bearing member 5 so as to secure an additional bearing surface and thereby distribute the bearing stresses throughout a considerable extent of the supporting casing and frame.

A convenient means of retaining the worm wheel in place is to provide annular aligning recesses within the worm wheel and casing at the surfaces 6 and 12 and to place therein a split spring ring or washer 16. This washer has its ends 17 drawn together against the inherent resiliency of the washer and when in such contracted position, its diameter is substantially that of the corresponding portion of the worm wheel. When in this condition, the worm wheel is slipped within the casing and the washer is allowed to expand thereby partially filling such annular recesses and holding the worm wheel in operative position within the casing.

The worm 18 is positioned within the housing 10 and at its thrust end is provided with a steel bearing washer 19 which is centrally recessed and carried upon a projecting reduced portion 20 of the worm 18. If desired, a suitable oil hole 21 may be provided through the casing 10 adjacent this bearing washer. The other end of the casing 10 is open and is adapted to be closed by a plate 22, through which extends the reduced portion 23 of the worm, and which

2

forms a bearing for such reduced portion. The casing 10 is provided with outwardly projecting slotted ears 24 and the plate 22 is provided with openings aligning with 5 such slots. Bolts 25 pass through such openings and slots and serve to retain the plate in position to close the worm casing 10. The plate 22 is continued laterally upon each side of the driving wheel 26 and forms 10 chain guides 27 upon each side of such wheel. These chain guides, it will be noted, are downwardly flared and at their upper ends approach more closely to the driving wheel so as to allow the driving chain to be 15 pulled at an angle to the driving wheel and still to retain such chain in the engagement with the driving wheel.

The load chain may have a loop 28 formed upon its slack side and one end of such loop 20 may be retained in a recess 29 formed in the member 3 of the supporting casing or frame. The other or load side of the chain extends downwardly as indicated at 30 in line with the axis of the supporting hook 11 25 and is usually provided with a load engaging hook 31.

In assembling the device, the worm 18 is first slipped into position with the bearing washer 19 thereon. The plate 22 and driving wheel 26 are next slipped over the reduced portion 23; the plate being bolted in place and the wheel secured upon such reduced portion by means of a set screw 32. Thereafter, the worm wheel is slipped 35 through the enlarged open end of the casing 1 while the spring washer 16 is in contracted position, it of course being understood that the hoisting drum 14 is slipped over the bearing member 5. When in final 40 position, the spring washer will expand and lock the worm and hoisting drum against lateral motion. The driving and load chains and the swivel supporting hook 11 are of course positioned upon the hoist in the 45 usual manner. To facilitate insertion of the worm wheel after the worm is in place, certain of the teeth of the worm wheel may be hobbed as indicated at 33 so that they may be slid over the worm when these teeth are 50 in the proper position.

It will thus be seen that a very small number of operations are required in assembling this hoist. The integral construction of the worm wheel and hoisting drum together with the integral construction of the bearing portions of the supporting casing insure an equalization of the stresses imposed upon the hoist and also a very desirable distribution of such stresses upon large 55 bearing surfaces which both decreases the 60

unit bearing pressure and also the stresses imposed upon any portion of such members.

I claim:

1. A hoist comprising a driving worm, a 65 driven worm wheel, a hoisting drum forming a unitary structure with said worm wheel, and a casing enclosing said worm and worm wheel and providing an exterior and an interior bearing for said worm wheel 70 and drum.

2. A hoist comprising a driving worm, a driven worm wheel, a drum operatively carried by said worm wheel, an open ended casing into which said worm wheel and drum are adapted to be slipped, and an annular spring disk having cooperative engagement with said worm wheel and said casing for retaining said worm wheel within 80 said casing.

3. A hoist comprising a driving worm, a driven worm wheel, a drum formed integrally with said worm wheel, and an open ended casing into which said worm wheel and drum are slipped, said worm wheel and drum having a sliding engagement with said casing, whereby said casing is completely closed by said drum and worm wheel, and whereby said casing supports said worm wheel. 90

4. A hoist comprising a driving worm, a driven worm wheel, a hoisting drum formed integrally with said worm wheel, and a casing surrounding said worm wheel and providing an exterior bearing therefor, and an 95 interior bearing for said hoisting drum.

5. A hoist comprising a driving member, a driven member, a drum formed integrally with said driven member, and a housing for said driven member, said housing and driven member cooperating to form an exterior bearing for said driven member, and said housing and drum cooperating to form an interior bearing member for said drum. 100

6. A hoist comprising a driving worm, a hollow cup-shaped worm wheel driven by said worm, a hoisting drum formed integrally with said worm wheel, a casing having a housing for said worm and an annular housing for said worm wheel, said worm wheel when in position within said casing serving to close such annular housing and arranged to have bearing engagement therewith, an annular split spring member having cooperative engagement with said worm wheel and casing and serving to retain said worm wheel and casing in operative relation, and an interior bearing for said drum formed integrally with said casing. 115
